UNITED STATES PATENT OFFICE.

LEWIS B. MOATS, OF JAMESTOWN, PENNSYLVANIA.

THILL-CO尤LING.

SPECIFICATION forming part of Letters Patent No. 380,452, dated April 3, 1888.

Application filed April 7, 1886. Serial No. 198,111. (No model.)

To all whom it may concern:

Be it known that I, LEWIS B. MOATS, residing at Jamestown, in the county of Mercer and State of Pennsylvania, a citizen of the 5 United States, have invented or discovered certain new and useful Improvements in Carriage-Clips, of which improvements the following is a specification.

In the accompanying drawings, which make 10 part of this specification, Figure 1 is a view in side elevation of my improved clip and thill or pole coupling. Fig. 2 is a top plan view of the same. Fig. 3 is a perspective view of the same on an enlarged scale.

15 The invention herein relates to certain improvements in clips employed in securing thills or poles to carriage-axles and in devices for connecting the clip and thill or pole, and has for its object such a construction of the clip 20 and its connections as will permit of the easy and rapid attachment and removal from the carriage-axle; and to this end the invention consists in the construction and combination of parts, substantially as hereinafter described 25 and claimed.

The clip 1 consists of a block of metal having an enlargement, 2, at one end, in which is formed a rectangular opening, 3, having its inner wall inclined, as shown in Fig. 1. In 30 the upper surface of the clip is formed a transverse groove, 4, for the reception of the axle 5, the clip being held in position on the axle by the band 6, of the usual form and construction. To the ends of the thill or pole 7 is bolted in the 35 usual manner the bifurcated block 8, provided with the depending lug 9, having a width equal to that of the rectangular opening in the head 2 of the clip. The outer face of the lug 9 is recessed, as shown in Fig. 1, thus forming 40 a rib, 10, at the lower end of the lug.

In using this device the lug 9 is inserted in the rectangular opening 3 in the head 2 and slid forward until the outer wall of the rectangular opening fits within the recess in the front side of the lug. A wedge, 11, having one 45 straight and one inclined side is then inserted into the rectangular opening between the lug and the rear wall of said opening. This wedge firmly keys the lug into position, the rib 10 engaging the under side of the head 2. The 50 wedge is held in position by a wire passing through the lower end of the wedge or by any other suitable device.

The construction above described is especially adapted for use where it is desirable or 55 necessary to remove the thills or poles in order to store the carriage or other vehicle.

I claim herein as my invention—

1. The combination of a carriage-clip rigidly secured to the axle and provided with a 60 slotted head, a block having a pivotal or hinged connection to the carriage thill or pole and provided with a depending lug constructed to fit in the slot in the clip-head, and a wedge, substantially as set forth. 65

2. A carriage-clip adapted to be rigidly secured to the axle and provided with a slotted head, in combination with a block having a pivotal or hinged connection to the carriage thill or pole and provided with a depending 70 lug, recessed as described, and a wedge, substantially as set forth.

In testimony whereof I have hereunto set my hand.

LEWIS B. MOATS.
